UNITED STATES PATENT OFFICE.

RICHARD D. ANANSON, OF STIRLING, NEW JERSEY, ASSIGNOR TO UNDERWOOD TYPE-WRITER COMPANY, OF NEW YORK, N. Y., A CORPORATION OF DELAWARE.

RIBBON MECHANISM FOR TYPEWRITERS.

Application filed March 24, 1922. Serial No. 546,305.

To all whom it may concern:

Be it known that I, RICHARD D. ANANSON, a citizen of the United States, and resident of Stirling, in the county of Morris and State of New Jersey, have invented certain new and useful Improvements in Ribbon Mechanism for Typewriters, of which the following is a specification.

This invention relates to auxiliary ribbon mechanism for typewriters and more particularly to the means for mounting the ribbon spools, advancing the ribbon and supporting it in its passage from one spool to the other.

15 One of the main objects of my invention is to provide an auxiliary ribbon attachment which may be readily attached to a typewriter of standard construction without necessitating alterations in the latter, and whereby the ribbon of the attachment may cooperate with the main ribbon of the machine to permit the typing of duplicate original copies from the two ribbons, and this irrespective of whether or not additional copies be made at the same time from carbon or other duplicating sheets.

20 Certain features of my invention are applicable for use either as parts of such an attachment, or the auxiliary ribbon mechanism may be substituted in the machine itself, as the main or single ribbon of the machine.

To this end, in the preferred form of the present invention, provision is made of an auxiliary ribbon frame mounted on the main frame at the back of the machine and bearing delivery and receiving spools for the auxiliary ribbon. A ribbon-guiding arm pivoted in the upper part of the auxiliary frame extends forward over the platen and is curved downward to carry the ribbon across the printing point at the front of the platen. The auxiliary ribbon extends forward along the upper surface of said downwardly curved ribbon-guiding arm substantially at right angles to the axis of the platen, across an aperture in the ribbon-guiding arm at the printing point and then is doubled back upon itself, and returns along the upper surface of the ribbon-guiding arm to the receiving spool at the rear of the machine. The aux-

iliary ribbon is thus rigidly supported at the printing point and is so guided to and from the printing point that it will not tend to obstruct the advance of the work-sheets nor 55 to smear them.

In accordance with one feature of the invention, provision is made of means for adjusting the ribbon-guiding arm longitudinally of the platen to move a fresh field of 60 the ribbon, which may have a plurality of color fields, into operative position.

The ribbon-guiding arm is pivoted far enough to the rear of the carriage so that it may be swung up completely out of the way 65 when sheets are to be inserted at the rear of the platen. The pivoting of the ribbon-guiding arm far to the rear of the platen is advantageous also because it results in a very large moment of force tending to swing 70 the arm about its pivot and press it against the platen while permitting the actual pressure upon the platen to be very slight. Due to this arrangement, the ribbon-guiding arm follows the platen immediately when 75 the platen is shifted from upper-case position, thereby maintaining the ribbon in operative position at all times, and this without exerting a pressure upon the work-sheets 80 which would cause interleaved carbon-sheets 85 to smear the work.

The escapement mechanism is connected to reciprocate a tooth that co-acts with a ratchet-wheel on the auxiliary ribbon-receiving spool to advance the spool step by step 85 to feed the ribbon. The arrangement is such that the pawl is moved idly on the printing stroke of the types and returns to feed the ribbon on the return stroke of the types, thus assuring that the ribbon will be stationary 90 at the time of the printing impact. Cam means acts to carry the pawl out of engagement with the ratchet-wheel in the latter part of its feeding stroke, and provision is made of means for adjusting the extent of the 95 stroke which will occur before such disengagement is effected.

Said cam means for disengaging the pawl and ratchet-wheel causes the pawl to be disengaged from the ratchet-wheel in its normal idle position so that it offers no obstruction to the turning of the auxiliary ribbon 100

receiving spool in either direction. Means are provided, independently of the step-by-step ribbon-feeding mechanism, for turning each of the spools to wind the ribbon 5 onto it from the other spool when desired.

In the drawings:

Fig. 1 is a vertical transverse section through a portion of a standard typewriting machine and my improved attachment,

10 Fig. 2 is a rear elevation of the attachment, certain of the parts being shown in section,

Fig. 3 is a sectional detail on the line 3—3 of Fig. 1,

15 Fig. 4 is a perspective view of the ribbon guide and in its relationship to certain of the parts of the machine,

Fig. 5 shows details of a portion of the ribbon in different positions for the action 20 of the type thereon, and;

Fig. 6 is a sectional detail of the adjustable pivotal support of the ribbon guide.

The Underwood Standard typewriter in connection with which I have illustrated my 25 invention includes a main frame 10 provided with guides 11 on which the traveling carriage 12 is mounted. This carriage supports the platen 13 around which the paper passes during the operation of the machine.

30 The main ribbon 14 is carried by a pair of spools (not shown) and in traveling from one to the other passes through a ribbon-guide or vibrator 15 adjacent a type-guide 16 through which the types move in striking the 35 ribbon 14 against the paper. The types 17 are carried by type bars 18 mounted to swing about pivots 19 and are actuated by bell-crank 20 connected to the key levers 21.

40 A rocker arm 22, forming part of the escapement actuating mechanism is connected to a universal bar 22^a in the path of the type-bars, and is also connected by mechanism, not shown, for operation by the usual space-bar, the arrangement being such that the 45 arm 22 is oscillated at each letter-space movement of the carriage. There may also be provided the usual means (not shown) for feeding the main ribbon 14 endwise with a step by step movement.

50 The parts so far described are of usual construction and are therefore illustrated only in so far as they cooperate with my improved attachment.

55 The attachment includes a bracket or auxiliary frame 30 which may be secured to the rear or base of the main frame of the machine in any suitable manner. As illustrated, this auxiliary frame includes a substantially horizontal plate 30 with an upstanding

60 lug 31 which may be rigidly secured in position by suitable screws 31'. Extending upwardly from the plate or frame portion 30 is a standard including a pair of side members 32 which are rigidly connected by suitable cross braces 33 and carry a pair of

spindles 34 and 35 for ribbon spools 36 and 37. These spools may be of standard construction. The two spindles 34 and 35 are disposed parallel and horizontal and the spools thereon are mounted in superposed 70

position with the end walls of one in the same vertical planes as the end walls of the other. The frame at its upper end has a third spindle or tie rod 38 upon which is pivotally mounted the ribbon guide 39. This 75 ribbon guide is preferably in the form of a sheet metal arm, as shown in Fig. 4 provided with an integral stiffening rib 39'.

At the pivoted end, the arm has oppositely disposed extensions 40 carrying lugs 41 bent 80 to lie in parallel planes. These lugs may be directly journaled on the spindle 38 although preferably they are mounted on a sleeve 42 which is carried by the spindle or tie rod 38. The sleeve also carries a roller 85

43 of a width corresponding to that of the ribbon, and of such diameter that the sleeve presents shoulders to prevent edgewise movement of the ribbon in respect to the roller. The pivotal support of the guide 90 is at an elevation somewhat higher than the platen, and in the rear thereof, and the guide extends forwardly over the platen and curves downwardly to a point on the front side thereof to the printing point. Adjacent to the free end of the guide, the latter has an aperture 44 of a length substantially equal to the width of the ribbon. The aperture may be of any desired width, although it is illustrated as being substantially square. 100

The terminal portion of the guide forms a transverse rounded bar 45 around which the ribbon may pass, as hereinafter more particularly pointed out. The ribbon guiding arm 39 and its aperture 44 are so positioned 105 that the aperture registers with the printing position of the type. In other words, each type as it swings into printing position passes through the type-guide 16, the ribbon-vibrator 15, and the aperture 44 of the ribbon guide 110 39. For supporting the free end of the ribbon guide and reducing to the minimum, its frictional engagement with the platen or the paper on the latter, the arm 39 may have a pair of oppositely disposed lugs 46 which 115 may have comparatively small projections or rounded knobs 47. The frictional engagement of these with the platen or paper therebeneath is comparatively small. The projections may also extend upwardly from the lugs or ears 46 so as to hold the paper out of engagement with the ribbon on the upper side of the ribbon guide.

120 The ribbon 50 is wound on one of the spools for instance, the upper spool 37, and passes from this spool over the roller 43 and thence lengthwise of the guiding arm 39 to the aperture 44. Here the ribbon passes through the aperture and around the terminal portion or bar 45, and back along the 130

upper surface of the first-mentioned run of the ribbon to the roller 43, thus forming a double-ply loop extending between the work-sheets B and C. From here it passes 5 downwardly to the other ribbon spool 36, preferably between the flanges 37 of spool 37.

Suitable means is provided whereby the receiving spool is rotated with a step by 10 step movement during the operation of the machine so that the ribbon is slowly fed from one spool to the other to bring fresh surfaces continually to operative position at the printing point 44. The mechanism 15 illustrated for this purpose includes a reciprocating link 51 which is pivoted to the rocker arm 22 of the machine, preferably by jaw 66 encircling cross pin 67 of said rocker arm and clamped closed by screw 68. At its 20 outer end, this link has a hook or pawl portion 52 coacting as a ratchet dog with a ratchet wheel 53 which may be locked to the lower spool 36. The dog 52 is held in operative position by means of a spring 54, 25 whereby during the pulling movement of the link 51, the ratchet wheel 53 and the spool 36 will be rotated while the dog may ratchet over the teeth during the return movement of the link. Preferably the link 51 is provided with an integral lug 60 pressed by 30 spring 54 against a stationary pin 61. The lug is widened at its end as at 63 to shift dog 52 downward out of contact with ratchet teeth 53 during the remainder of the stroke 35 of link 51 in the operative direction after completion of the feeding step. The link is, moreover, provided with a turnbuckle 64 by which its length and consequently, the length of the ribbon feed steps can be 40 adjusted. Return rotation of the ratchet wheel may be prevented by a suitable dog or pawl 55 pivoted to cross-bar 33 and over-running of the spool may be prevented by a spring friction brake 56, also mounted on cross-bar 33. The upper spool 37 may also have a 45 friction brake 57 pressing against the ribbon thereon, thus preventing the unwinding of the ribbon from the spool, except at such rate as is required by the positive rotation 50 of the lower spool. The type-bars 18 engage the universal bar 22 as they near the printing point, and this in turn rocks the arm 22 to move the link 51 to the rear. The rearward movement of the link 51 is an idle 55 movement, however, so that the ribbon 50 remains stationary until after the type has struck. During the return stroke of the type-bar the universal bar 22 is drawn forward by a spring (not shown) to rock the arm 22 forward and actuate the link 51 to feed the ribbon 50.

The ribbon may be of uniform color throughout its width, or it may be polychrome, in other words divided longitudinally into two or more sections *a*,

b, and *c*, of different colors, as shown in Fig. 5. In order to bring the sections of different colors into operative position or to permit the different sections to be fully utilized if the ribbon be of a single color, I 70 provide means whereby the ribbon guide 39 may be shifted endwise of the supporting rod 38. This is shown particularly in Fig. 6. The rod is shown as being provided with a plurality of parallel transverse holes 59, any one of which may receive a locking pin 60' carried by the sleeve 42 and passing through corresponding apertures therein. With the pin in one hole, as shown in Fig. 6, one edge portion of the 80 ribbon will be in operative position in respect to the type. By moving the pin to the next hole 59, the center portion of the ribbon will come into play, and by moving it to the third hole, the other edge portion 85 will come into operation. Of course, a greater or lesser number of adjustments than shown may be provided.

For feeding the ribbon at will endwise independently of the normal step by step feeding movement, or for returning the ribbon to the upper spool 37 after it has passed through operative position to the lower spool, I provide means whereby either spool 90 may be rotated in either direction at will. 95 As shown, the upper spindle 35 has a clutch collar 62 and a crank 63', the clutch being normally held out of operative position by means of a coil spring 64'. A spring 66" bears against the clutch to maintain the 100 spindle 35 in its bearings. The lower spindle 34 has a clutch collar 65 which may be rigid with the ratchet wheel 53 and which is normally held in locking engagement with the spool 36 by a coil spring 66'. This spindle 105 also has a crank 67'. The pawl 52 is held out of engagement with the ratchet-wheel 53 by pin 61, in the idle positions of the parts. After engaging the clutch 62 and lifting the pawl 55 by depressing finger 110 piece 55', therefore, the operator may rotate the upper spool to return the ribbon from the lower one. With the parts in normal position as shown in Fig. 2, the lower spool may be positively rotated at any time desired to transfer the ribbon, or any desired portion of the ribbon to it, from the upper spool. The spindles 35 and 34 may be moved endwise against the force of their springs 66" and 66' sufficiently to permit 115 new spools to be substituted upon them, when desired, the springs 56 and 57 being sufficiently flexible to bend back clear of the flanges of said spools.

In the use of my improved device, it 125 will be noted that the auxiliary or supplemental ribbon has a portion at the printing point on the platen, and that the ribbon is advanced with a step by step movement during the operation of the machine, so as 130

to continually bring fresh portions of the ribbon into play, and that this positioning and feeding of the auxiliary ribbon is independent of the main ribbon. It will also be noted that two thicknesses of the ribbon cross the printing point or aperture 44 of the guide.

The ribbon guide 39 is raised about its pivotal support 38 to permit sheets of paper 10 A, B, C, to be passed about the platen in the usual manner, after which the ribbon guide 39 is returned to its position of rest against the platen. The upper sheets A and B may be caused to extend over the 15 ribbon guide 39 and the sheet C may be caused to extend beneath it, as shown in Fig. 1. When the machine is operated, the types will strike the main ribbon 14, to print on the outer sheet A. At the same 20 time, the outer surface of the ribbon 50 at the aperture 44 will print with mirror script against the rear or under side of the sheet B. The other or under layer of the ribbon 50 will print directly on the outer 25 or front surface of the sheet C. Thus, there will be produced two original copies made directly from the two ribbons on the two sheets A and C. There will also be produced the mirror script copy on sheet B. 30 This sheet should be of onion skin paper or other such translucent material as will permit the typewriting to be read through the sheet from the front surface. Inasmuch as 35 this is in mirror script, which cannot be produced with an ordinary typewriter, directly from the ribbon, it will be apparent that such a copy cannot be altered on any ordinary typewriter, and therefore, constitutes a permanent record of the subject-matter as originally typed. Obviously, 40 where the mirror script copy is not required, a single intermediate sheet could be used indefinitely to take the imprint from the forward run of ribbon 50, thus maintaining 45 the rear of sheet A clean.

If at any time it is desired to use the typewriter without the auxiliary ribbon attachment, it is not necessary to remove the latter from the machine, but the ribbon 50 guide 39 need merely be shifted to the rear about its pivot.

It will, of course, be evident that any desired number of supplementary sheets with 55 interposed layers of carbon or other reproducing material may be employed between the sheet C and the platen, as in the ordinary use of a typewriting machine. Furthermore, the ribbon 50, instead of being an inked ribbon, may be a plain strip of paper, 60 and by omitting the sheets A and B, or by substituting carbon paper for the sheet B, the typed matter will appear on the strip of paper which is used in place of the ribbon 50, and this typed subject-matter will 65 form one continuous line lengthwise of the

strip. By shifting the guide 39 along the spindle or support 38, after the length of the strip has been fed past the type, a second such line and then a third may be typed on the strip. If desired, a strip of paper, 70 preferably translucent, may be used in place of ribbon 14, upon which ribbon 50 would print a continuous mirror script record, which can readily be read through the paper. 75

Inasmuch as the guide 39 of the ribbon 50 extends in a direction at substantially right angles to the axis of the platen, and transversely of the direction of endwise movement of the platen, only a comparatively narrow width of guide and ribbon are exposed for frictional engagement with the paper, and the resistance to the endwise movement of the platen is very much less than in the case where the auxiliary or interposed ribbon extends lengthwise of the platen along substantially the full width of the superposed sheets. Due to the fact that the guide and the ribbon extend longitudinally of the paper, rotation of the platen for line feeding will not shift nor twist the run of ribbon laterally, as may sometimes occur where the ribbon runs parallel to the platen. Furthermore, the ribbon is firmly supported at the printing point, so that 80 there is no danger of displacing the ribbon during a rotation of the platen, as is the case where such ribbon extends lengthwise of the platen and is unsupported at the 85 printing point. 90

It will be seen that the heights of the letter impressions extend longitudinally of ribbon 50, so that there is no possibility of striking the tops or bottoms of the type beyond the edge of the ribbon, and thereby 95 printing but a fraction of the letter, as may sometimes occur where the transverse ribbon is used on its extreme upper or lower setting in the former case, particularly in 100 printing capitals.

It will, of course, be obvious that, if desired, the auxiliary ribbon attachment may be permanently built into the typewriter as a part thereof, instead of, or in addition to the conventional ribbon mechanism. It will further be apparent that in either case, the common type of ribbon shift key may be provided instead of the means shown in 115 Fig. 6.

It will thus be seen that there is herein 120 described apparatus in which the several features of this invention are embodied, and which apparatus in its action attains the various objects of the invention and is well suited to meet the requirements of practical use.

Variations may be resorted to within the scope of the invention, and portions of the improvements may be used without others.

Having thus described my invention, what 130

I claim as new and desire to secure by Letters Patent is:

1. In a typewriting machine, the combination with a main frame, a carriage thereon, a platen on said carriage and printing instrumentalities to print through a main ribbon against said platen, of means to conduct an auxiliary ribbon from the delivery side of the platen to the printing point and between work-sheets, said means including a ribbon-guide supported on the main frame, said guide being flat and thin at its free end so that it may extend between the work-sheets without disturbing their printing relation and in a direction opposite to which the work-sheets are fed around the platen, and means to feed said auxiliary ribbon.
2. In a front-strike typewriting machine, the combination with a main frame, a carriage thereon, a platen on said carriage and printing instrumentalities to print through a main ribbon against said platen, of means to conduct an auxiliary ribbon from the delivery side of the platen to the printing point and between work-sheets, said means including a pair of ribbon-spools at the rear of the machine, and a ribbon-guide to conduct the auxiliary ribbon at right angles to the main ribbon, said ribbon-guide being supported on the main frame and extending between the work-sheets to conduct the auxiliary ribbon to the printing point, and means to feed said auxiliary ribbon.
3. An attachment for a typewriter having a platen, type carriers and a ribbon extending lengthwise of the platen, said attachment including a ribbon guide projecting over and downwardly in front of the platen and having an aperture therein adjacent to the end thereof, and means for causing a ribbon to pass along the upper surface of said guide, through said aperture and back along the upper side of the guide.
4. In a front-strike typewriting machine, the combination of a platen around which an outer work-sheet and an inner work-sheet may be fed, means to vibrate a main ribbon in front of the outer sheet, a stationary ribbon-guide extending over the platen and down at the front thereof to the printing point and between the work-sheets to guide an auxiliary ribbon to the printing point, and feeding means for said ribbons, one of said ribbons extending perpendicularly to the other.
5. In a typewriting machine, the combination of a platen, ribbon-spools arranged in the same vertical plane behind the platen and perpendicularly thereto, a ribbon-guide extending from the spools over the platen to the printing point to guide the ribbon from the spools to said printing point, and means to adjust the ribbon-guide sidewise to vary the printing field of the ribbon.
6. A typewriter having an arm provided

with an aperture adjacent to the free end thereof and registering with the printing position of the type, the terminal portion of said arm serving to support the loop of a ribbon with the runs of the ribbon to and from said loop, along one and the same surface of the arm and one run extending through said aperture.

7. A typewriter having an arm provided with an aperture adjacent to the free end thereof and registering with the printing position of the type, the terminal portion of said arm serving to support the loop of a ribbon with the runs of the ribbon to and from said loop, along one and the same surface of the arm and one run extending through said aperture, and means for advancing said ribbon step by step in the direction of its length.

8. A typewriter having an arm projecting forwardly and curved downwardly over the platen and having an aperture adjacent to the free end thereof and registering with the printing position of the type, the terminal portions of said arm serving to support the loop of a ribbon with the runs of the ribbon to and from said loop in superposed position along said arm, and one run extending through said aperture.

9. A typewriter having a ribbon guide provided with an aperture registering with the printing position of the type and the terminal portion of said guide serving to support the loop of a ribbon with the runs of the ribbon to and from said loop lengthwise of the guide in superposed position, and means for holding separate strips of paper adjacent to the opposite sides of the two runs of the ribbon at said aperture, whereby both sheets may be printed on simultaneously.

10. A typewriter having a ribbon guide presenting an aperture and a terminal portion around which the ribbon may pass with separate runs of the ribbon in superposed relationship at said aperture, and means for holding said guide between separate sheets of paper, whereby both runs of the ribbon are in operative position in respect to said sheets at said aperture.

11. A typewriter having a ribbon guiding arm extending forwardly and curved downwardly in front of the platen, a pivotal support for the rear end of said arm, said arm being adjustable at said pivotal support in the direction of the axis of the platen to bring different portions transversely of the ribbon into operative position.

12. An attachment for typewriters including a frame, means for securing it to the rear of the frame of a standard typewriter, said attachment frame including supports for a pair of ribbon spools, means adapted for connection to the operating mechanism of the typewriter, for automat-

- ically rotating one of said spools step by step during operation of the machine, and a ribbon guide extending forwardly over the platen, and then downwardly to the printing point to conduct the ribbon from the spools to the printing point, said ribbon guide having an aperture through which the printing takes place.
13. An attachment for typewriters including a frame having a pair of standards, parallel spindles carried thereby for supporting ribbon spools, a ribbon guiding arm pivoted to said frame and presenting a part around which the ribbon passes from one spool to the other, and means for adjusting said arm in the direction of the axis of said spools independently of the latter.
14. An attachment for typewriters including an auxiliary frame, means for supporting a pair of ribbon-spools thereon, a guide around which the ribbon passes from one spool to the other and serving to support a portion of the ribbon in operative position with respect to the printing point of the machine, a ratchet-wheel connected to one of the spools, a link arranged to be connected to the operating mechanism of the typewriter and having a tooth for engaging and feeding said ratchet-wheel, means for holding the tooth out of engagement with the ratchet-wheel while the link is in its inoperated position, and means for yieldingly pressing the tooth into engagement with the ratchet-wheel during the operative stroke of the tooth in the direction along the periphery of the ratchet-wheel.
15. In a typewriting machine, a ribbon, a pair of ribbon-spools and ribbon-feeding mechanism comprising a ratchet-wheel connected to rotate one of the spools, a pawl movable to rotate the ratchet-wheel step by step, a link connected to said pawl, operating means for the pawl, a cam to disengage the pawl and ratchet-wheel during the operative stroke of the pawl to control the extent of ribbon-feeding, and means adjustable on said link to vary the stage at which the pawl is withdrawn from engagement with the ratchet-wheel and thereby to vary the extent of ribbon-feeding.
16. In a typewriting machine, in combination, a ribbon, delivery and receiving spools therefor, a ratchet-wheel connected to rotate the receiving spool to feed the ribbon, a reciprocating pawl movable to rotate the ratchet-wheel step by step, means yieldingly urging the pawl toward the ratchet-wheel at each reciprocation, positively acting means for taking the pawl out of engagement with the ratchet-wheel upon each return stroke to normal position thereof, and means for rotating the delivery spool to wind the ribbon onto it from the receiving spool when the pawl is in its normal disengaged position.
17. In a typewriting machine, in combination, a ribbon, delivery and receiving ribbon-spools, a ratchet-wheel connected to rotate the receiving spool to feed the ribbon, a reciprocable link having a tooth to rotate the ratchet-wheel step by step, a spring yieldingly pressing the tooth toward the ratchet-wheel, a cam to disengage the tooth from the ratchet-wheel during the operative stroke of the link to control the extent of ribbon-feeding, and means for adjusting the effective length of the link to vary the stage at which the cam will become effective.
18. In a typewriting machine, in combination, a ribbon, delivery and receiving ribbon-spools, a ratchet-wheel connected to rotate the receiving spool to feed the ribbon, a reciprocable link having a tooth to rotate the ratchet-wheel step by step, a spring yieldingly pressing the tooth toward the ratchet-wheel, and means operating on the link to disengage the tooth from the ratchet-wheel during the operative stroke of the link to control the extent of ribbon-feeding, the link including a turn buckle to adjust its length to vary the stage at which the disengaging means becomes effective.
19. In a typewriting machine, in combination, a ribbon, delivery and receiving ribbon-spools, a ratchet-wheel connected to rotate the receiving spool to feed the ribbon, a reciprocable member for rotating the ratchet-wheel step by step, an escapement-actuating frame to which said reciprocable member is connected, said reciprocable member being movable in one direction idly and in the other direction to advance the ratchet-wheel, the movement of the escapement-actuating frame being greater than that required to advance the ratchet-wheel, and means to withdraw the reciprocable member from the ratchet-wheel during its operative stroke and prior to reaching normal to limit the extent of ribbon-feed at each stroke.
20. In a typewriting machine, a ribbon, delivery and receiving spools therefor, a spindle on which the delivery spool is mounted, a clutch on the spindle for rotating the delivery spool to wind the ribbon back from the receiving spool, a spring urging the spindle in the direction to disengage the clutch, and a second spring urging the spindle in the opposite direction to maintain the spindle in its bearings, the spindle being normally balanced between the two springs in position to hold the clutch disengaged, the construction and arrangement being such that the spindle may be thrust lengthwise in one direction against the force of the first-mentioned spring to engage the clutch with the delivery spool and may be also thrust in the opposite direction against the force of the second-mentioned spring to withdraw it from one of its bearings suf-

ficiently to permit the removal of the spool from the spindle.

21. In a typewriting machine, a frame, a traveling carriage, a platen in the carriage shiftable between lower case and upper case writing positions, ribbon-carrying means mounted on the frame independently of the carriage and to the rear thereof, and a ribbon-guide extending forward over the platen 10 to guide the ribbon to the printing point, the ribbon-guide being pivotally mounted beyond the rear of the carriage to be swung up out of the way when work-sheets are being inserted around the platen and to permit the 15 forward end of the guide to participate in the up-and-down movement of the platen in case-shifting, the pivot of the ribbon-guide being located so near to the ribbon path that the turning of the guide about said pivot 20 will not substantially tension nor slacken the ribbon.
22. A manifolding attachment for typewriters comprising a movable arm mounted upon a stationary portion of the machine 25 frame and thence extending above and clear of the platen carriage to the region of type

impact; a manifolding member carried by said arm and adapted to be moved thereby into and out of functional position in the line of type impact, between the sheets of 30 paper to be typed; and means dependent upon the operation of the machine in typing, for varying the surface point of the manifolding member exposed to the type impact.

23. A manifolding attachment for type-writers comprising a movable arm mounted upon a stationary portion of the machine frame and thence extending above and clear of the platen carriage to the region of type impact; a manifolding member carried by 35 said arm and adapted to be moved thereby into and out of functional position in the line of type impact, between the sheets of 40 paper to be typed; and means actuated by the word-spacing bar of the machine for 45 varying the surface point of the manifolding member exposed to the type impact.

Signed at New York in the county of New York and State of New York this 23rd day of March, 1922 A. D.

RICHARD D. ANANSON.
